UNITED STATES PATENT OFFICE.

THOMAS N. DELIGIANES AND ANDREAS A. BOURDES, OF CHICAGO, ILLINOIS, AS-SIGNORS, BY MESNE ASSIGNMENTS, TO GEORGE D. ANTHOULIS, OF GARY, INDIANA.

PAPER-FOLDING DEVICE.

Application filed April 28, 1923. Serial No. 635,312.

This invention relates to paper folding devices, and an object of the invention is to provide a device for folding paper, a plurality of times, in which a plurality of forms 5 are provided and arranged relative to each other to successively engage the paper and guide it to folding rolls for providing a plurality of folds in the paper, and further to provide adjustable mountings for the various forms to permit their adjustment for properly engaging and folding paper of different sizes as well as to permit their adjustment for changing the location of the folds in the paper.

15 A further object of this invention is to provide suitable guards at the free ends of the forms which engage the paper and prevent the edges from curling back and being improperly creased as well as to facilitate 20 the flatwise guiding of the paper to the folding rolls.

Another object of this invention is to provide a folding device which is applicable for use upon the napkin folding machines as disclosed in the application on napkin machines, filed April 4, 1922, Serial No. 549,534, and September 22, 1922, Serial No. 589,834.

Other objects of the invention will appear in the following detailed description 30 taken in connection with the accompanying drawings wherein:—

Fig. 1 is a longitudinal section through the improved paper folding mechanism.

Fig. 2 is a vertical section on the line 2—2 of Fig. 1.

Fig. 3 is a detail section on the line 3—3 of Fig. 1.

Fig. 4 is a detail cross section on the line 4—4 of Fig. 3.

Fig. 5 is a detail vertical section on the line 5—5 of Fig. 1.

Fig. 6 is a cross section on the line 6—6 of Fig. 5.

Referring more particularly to the drawing the improved paper folding mechanism comprises a suitable supporting structure 1 which includes inclined supporting bars or braces 2 and suitable supporting means 3 for a roll of paper as shown at 4. The strip of paper from the roll passes over the advance folding form 5 which is of triangular shape in top plan and has its base at the receiving end and its apex arranged adjacent a sleeve 6 and the roller 7. The form 5 is pivotally mounted, at its receiving end, upon a suit-

able supporting rod 8 and it swings free from the supporting rod, having its free end adjustably supported against accidental movement by a suitable adjusting screw 9. The adjusting screw 9 is threaded through a bracket 10 secured to a bar 10^a connecting the supports or braces 2.

The sleeve 6 is vertically adjustable relative to the roll 7 and also relative to the initial folding form 5. The receiving end of the second folding or guiding form 11 is attached to the sleeve 6, and in fact is extended and mounted about the sleeve, as clearly shown in Fig. 6 of the drawings, so that

the second form 11 will be adjusted vertically upon vertical adjustment of the sleeve 6.

65 The bore 12 of the sleeve 6 is threaded and receives therethrough the threaded feeding screw 13 which is rotatably supported at one end by the supporting structure 1 and at its opposite end by the bight portion 70 14 of the inverted U shaped support 15.

The feed screw 13 is held against longitudinal movement by means of a collar 16, and a thumb nut 17 is pinned upon the feed screw 75 for rotating it to vertically adjust the sleeve 6 and the second folding or guiding form 11.

80 The second folding or guiding form 11 is of the same shape as the form 5, however, it is much smaller in size and has its base positioned sideways or transversely to the manner in which the base of form 5 is positioned

so that it will fold the paper a second time and guide it to the substantially horizontal creasing or folding roller 18 and rod 19. The 85

folding or guiding form 11 is braced by a brace 20 which is in turn connected by means of a cap screw 21 to a sliding block 22 which is adjustably carried by a suitable guide 23.

The guide 23 is in turn attached to one of 90 the legs of the inverted U shaped support 15.

The roller 18 and rod 19 have their ends journaled in bearing boxes 24 which are adjustably carried by suitable guiding supports 25.

100 Adjusting screws 26 are rotatably connected to the bearing boxes 24 and are threaded through adjusting nuts 27 so that upon rotation of the adjusting nuts the elevation of the roller 18 and rod 19 may be regulated in accordance with the adjustment of the form 11.

105 From the roller 18 and rod 19 the paper passes over a third, and in the construction shown in the drawings, final folding or guiding form 28 which is shaped similar to 110

the other folding forms, being smaller in size, however. The folding form 28 rests in substantially vertical position and has its triangular face facing forwardly or outwardly. The base end of the triangle face of the folding form 28 is rolled about the cylinder 19 forming a sleeve 29 which is slideable upon the rod 19 and is held in adjusted position thereon by means of a set 10 screw 30. The form 28 is braced by an adjustable bracing bolt 31 which is carried by a suitable support 32. The support 32 is slotted as shown at 33 to permit vertical adjustment of the bolt 31, and the bolt 31 is 15 held in longitudinally adjusted positions relative to the support 32 by means of lock nuts 33^a. The support 32 has an attaching base 34 thereon which is provided with an elongated slot 35 through which cap screws 20 36 extend for holding the support 32 in adjusted positions upon the supporting structure 1.

Substantially U shaped guides 37 are carried by each of the forms 5, 11 and 28. The 25 guides 37 are formed of wire and extend along the delivery edges of the forms having their bright portions and the major lengths of their legs spaced from the respective forms, as clearly shown in Figs. 3 and 4 of 30 the drawings. The terminals of the legs of the U-shaped guides 37 are soldered or otherwise suitably attached to the forms 5, 11 and 28, as shown at 38 and they are adapted to guide the paper being folded, over the delivery ends of the respective forms and prevent curling and improper creasing of the edges of the paper.

From the form 28 the paper passes downwardly between the final pair of folding 40 rollers 39 and 40. The roller 40 is rotatably supported by suitable bearing blocks 41 which are in turn adjustably supported from the supporting structure 1 so as to permit movement of the roller 40 towards or from 45 the roller 39. Feed screws 42 are connected to the bearing boxes 41 and are adapted to move the bearing boxes 41 in their guide slots 43 upon rotation of the feed screw 42. In the operation of the folding mechanism, 50 a strip of paper drawn over form 5 is folded along a central longitudinal line and is then creased by passing between roller 7 and sleeve 6. The folded strip is again folded along a central longitudinal line as it 55 passes over form 11 and between roller 18 and sleeve 29, and it then passes over form 28 and between rollers 39 and 40 so as to be again folded along a central longitudinal line and then creased. The supporting rods 60 and the sleeves of the forms fitting about the rods provide hinged or pivotal mountings permitting adjustment of the forms in the manner above described.

While in the foregoing description and 65 the drawings only three forms have been

disclosed together with the companion sets of folding rollers it is to be understood that any number of the folding forms may be arranged in sequence, depending upon the size of the paper to be folded and the number of folds to be made in the paper.

From the foregoing description taken in connection with the accompanying drawings it will be apparent that the paper taken from the roll 4 will be drawn over the respective guiding and folding forms, and that during this passage over each form and the folding members associated therewith, the paper will be folded and creased so that after it issues from the final pair of rollers, the paper can be led to any suitable mechanism for further treatment. It is to be understood that the paper may be drawn over the various folding rollers and through the various creasing members in any suitable manner such as by the mechanism shown in the applications heretofore referred to. By adjustment of the various folding rollers and creasing members, the exact location of the various folds or creases may be varied as desired and the various rollers and creasing members may be adjusted to properly fold paper of different sizes. The adjustment of form 28 is of particular importance as insuring creasing of the strip centrally thereof and proper delivery of the strip to the rollers 39 and 40. By means of bolt 31, the slotted support 32 and nuts 33^a the form 28 can be easily adjusted vertically about rod 19 and rectilineal adjustment of this form transversely thereof and parallel to its forming surface can be readily effected by means of the slotted base 34 and the cap screws 36.

The forming face of form 28 is the face over which the strip passes or is drawn to be creased or folded, and is the upper surface or face of this form as viewed in Fig. 2. It will be noted that the transverse adjustment of form 28 is effected by rectilineal movement of the form, this adjustment being also transversely of or at right angles to the strip of material passing over the form as well as at right angles to the direction of travel of the strip over the form. This feature is of value in compensating for any side pull of the strip. It frequently happens that the paper used for forming the napkins has a tendency to pull or stretch more at one side of the strip than the other, as it is pulled off of the roll of paper 4 and over the forms. This is particularly true of crepe paper, though it is also true to a greater or less degree of other papers used for making paper napkins. This side pull would render it impossible to fold the paper strip accurately and to obtain proper delivery of the folded strip to the rollers 39 and 40 unless some means of neutralizing or compensating for the side pull of the paper were provided. This result is

obtained by adjusting the form 28 transversely and in a straight line in a proper direction and sufficiently to overcome the side pull of the paper strip. The proper adjustment of the form is to be determined by experiment for each roll of paper. It will also be noted that the form 11 can be adjusted transversely of its forming face by means of screw 13, this adjustment being also rectilinear. The adjustability of form 11 provides means supplemental to the adjustability of form 28 for overcoming side pull of the paper and insuring accurate folding of the strip and proper delivery thereof to the rollers 39 and 40.

It is, of course, to be understood that the invention may be constructed in other manners and the parts associated in different relations and, therefore, I do not desire to be limited in any manner except as set forth in the claims hereunto appended.

Having thus described my invention what I claim is:-

1. In a machine of the character stated, a plurality of folding forms disposed in alignment to successively fold a strip of material passed over the forms, and means for adjusting certain of said forms transversely and parallel to the forming surfaces thereof.

2. In a machine of the character stated, a plurality of folding forms disposed in alignment to successively fold a strip of material passed over the forms, and means for adjusting certain of said forms in a plane at right angles to and transversely of the strip passing over the forms to compensate for side pull of the strip.

3. In a machine of the character stated, a plurality of folding forms disposed to successively fold a strip of material passed over the forms, and means for adjusting one of the forms transversely and parallel to the forming surface thereof.

4. In a machine of the character stated, a plurality of triangularly shaped folding forms disposed in alinement to successively fold a strip of material passed over the same, and guiding and creasing means mounted between said forms, said means acting to support certain of said forms.

5. In a machine of the character stated, a plurality of triangularly shaped folding forms disposed in alinement to successively fold a strip of material passed over the same, supporting rods, the forms having supporting sleeves fitting about the rods, and rollers positioned adjacent certain of said sleeves and coacting therewith to guide the strip and to crease it during its travel from one form to the succeeding form.

6. In a machine of the character stated, a plurality of triangularly shaped folding forms disposed in alinement to successively fold a strip of material passed over the same, supporting rods, the forms having

supporting sleeves fitting about the rods, rollers positioned adjacent certain of said sleeves and coacting therewith to guide the strip and to crease it during its travel from one form to the succeeding form, and means for adjusting the forms on the supporting rods.

7. In a machine of the character stated, a plurality of triangularly shaped folding forms disposed in alinement to successively fold a strip of material passed over the same, supporting rods, the forms having supporting sleeves fitting about the rods, rollers positioned adjacent certain of said sleeves and coacting therewith to guide the strip and to crease it during its travel from one form to the succeeding form, and means for adjusting the forms on the supporting rods independently of each other.

8. In a paper folding device, an initial folding form, means pivotally supporting said folding form, adjustable means engaging said form for holding it in adjusted positions, a second folding form for receiving the paper from said initial folding form, means for vertically adjusting said second form, guiding and creasing means between said forms, and vertically adjustable horizontal guiding and creasing means positioned at the delivery end of said second form.

9. In a paper folding device, an initial folding form, means pivotally supporting said folding form, adjustable means engaging said form for holding it in adjusted positions, a second folding form for receiving the paper from said initial folding form, means for vertically adjusting said second form, creasing and guiding means between said forms, vertically adjustable horizontal creasing and guiding means positioned at the delivery end of said second form, a folding form pivotally carried by the last named creasing and guiding means and adjustable longitudinally thereof, and means for holding said last named form in adjusted positions.

10. In a paper folding device, an initial folding form, means pivotally supporting said folding form, adjustable means engaging said form for holding it in adjusted positions, a second folding form for receiving the paper from said initial folding form, means for vertically adjusting said second form, creasing and guiding means between said forms, vertically adjustable horizontal creasing and guiding means positioned at the delivery end of said second form, a folding form pivotally carried by the last named creasing and guiding means and adjustable longitudinally thereof, means for holding said last named form in adjusted positions, a pair of folding rolls for receiving the paper from said last named folding form, and means for adjusting the position

of one of said last named folding rolls relative to the other.

11. In a machine of the character stated, a folding form mounted for vertical and horizontal adjustment, means for adjusting said form vertically, and means for effecting horizontal rectilineal adjustment of the form.

12. In a machine of the character stated, a triangular folding form, means for adjusting said form transversely and in a plane parallel with its forming surface, a second folding form disposed to receive a folded strip of material from the first form and having its forming surface disposed at right angles to the forming surface of the first form, means for adjusting the second form transversely and in a plane parallel with its forming surface, and means for adjusting said second form vertically.

13. In a machine of the character stated, a triangular folding form, means for adjusting said form transversely and in a plane parallel with its forming surface, a second folding form disposed to receive a folded

strip of material from the first form and 25 having its forming surface disposed at right angles to the forming surface of the first form, means for adjusting the second form transversely and in a plane parallel with its forming surface, and means for adjusting 30 said second form vertically.

14. In a paper folding device, a substantially triangularly shaped folding form, means for vertically adjusting said form, 35 creasing and guiding means at the delivery end of said form for receiving paper from the form, means for vertically adjusting said creasing and guiding means, a folding form pivotally carried by the creasing and guiding means and mounted for adjustment 40 longitudinally thereof, and means for holding said last named form in adjusted positions.

In testimony whereof we affix our signatures.

THOMAS N. DELIGIANES.
ANDREAS A. BOURDES.
